(57) **CLAIM**

The ornamental design for the hot water kettle, as shown and described above.

DESCRIPTION

FIG. 1 is a perspective view of a hot water kettle showing my new design from the right front;

FIG. 2 is a front elevation of the hot water kettle of FIG. 1;

FIG. 3 is a rear elevation of the hot water kettle of FIG. 1;

FIG. 4 is a right side elevation view of the hot water kettle shown in FIG. 1;

FIG. 5 is a left side elevation view of the hot water kettle shown in FIG. 1;

FIG. 6 is a top plan view of the hot water kettle of FIG. 1; and, FIG. 7 is a bottom plan view of the hot water kettle shown in FIG. 1.

The broken lines in the drawings are included for the purpose of illustration and form no part of the claimed design.
